UNITED STATES PATENT OFFICE.

EDWARD A. FARR, OF MERIDEN, CONNECTICUT, ASSIGNOR TO MANNING, BOWMAN & COMPANY, OF MERIDEN, CONNECTICUT, A CORPORATION OF CONNECTICUT.

DESIGN FOR A CHAFING-DISH.

42,563.

Specification for Design.

Patented May 28, 1912.

Application filed December 26, 1911. Serial No. 668,003. Term of patent 7 years.

To all whom it may concern:

Be it known that I, EDWARD A. FARR, a citizen of the United States, residing at Meriden, New Haven county, Connecticut, have invented a new, original, and ornamental Design for a Chafing-Dish, of which the following is a specification, reference being had to the accompanying drawing, forming a part thereof, in which the figure

shown is a side elevation of the complete dish.

I claim:

The ornamental design for a chafing dish, as shown.

EDWARD A. FARR.
